(57) **CLAIM**

The ornamental design of a cooler and jug construction, as
shown and described.

DESCRIPTION

FIG. 1 is a perspective view of the inventive design from
above and from one side thereof;

FIG. 2 is a perspective view of the design from below and
from the side opposite that shown in FIG. 1;

FIG. 3 is a side elevation of the design, it being understood
that the opposite side is a mirror image of that shown in FIG.
3;

FIG. 4 is a top plan view of the design;

FIG. 5 is a bottom plan view of the design;

FIG. 6 is a side elevation taken from the right of FIG. 1; and,
FIG. 7 is a side elevation taken from the left of FIG. 1.
